HAND COMPOSING DEVICE

George J. H. Sausele, West Hempstead, N. Y., assignor to Intertype Corporation, Brooklyn, N. Y., a corporation of New York

Application December 24, 1951, Serial No. 263,058

7 Claims. (Cl. 99—4.5)

1

This invention relates generally to typographical machines for photographically reproducing on a sensitized film or paper lines of type matter from composed lines of individual character-bearing elements or matrices. More particularly the invention relates to an improved, hand-composing stick for supporting a hand-composed line of such matrices. The composing stick of the present invention is particularly useful in connection with photo-composing machines of the type disclosed in Freund application Serial No. 237,696, filed July 20, 1951, and will be illustratively described in connection with such apparatus, although as the description proceeds it will be apparent that the composing stick can be used with other types of apparatus as well.

In using one embodiment of the apparatus disclosed in Freund et al., application Serial No. 237,696, a line of character-bearing matrices is assembled manually in a composing device usually called a composing stick, and the assembled line supported in the composing device is inserted in the machine in such a way as to position the line within an elevator. The line is then transferred by the elevator and associated mechanisms to a justifying station at which a justification measurement is made, and thereafter the characters of the elements are individually and sequentially photographed on a movable film, the film movement being correlated with the justification measurement to produce justified lines of type matter on the film.

It is an object of the present invention to provide an improved composing stick for supporting a series of character-bearing elements as they are manually composed. It is another object of the invention to provide a composing device of this type that is readily insertable in a photo-composing machine and so constructed as to position the composed line of matrices accurately within the elevator or equivalent portion of the machine. It is still another object of the invention to provide a composing device that permits ready removal of the composed line of matrices as a unit therefrom. It is a still further object of the invention to provide a hand composing device wherein the line length can be easily and accurately adjusted to a desired value. Other objects of the invention will be in part obvious and in part pointed out hereafter.

The many objects and advantages of the present invention can best be understood and appreciated by reference to the accompanying drawing, wherein:

Fig. 1 is a general perspective view of the composing device showing the relationship of the as-

2

sembler slide and gauging member to the slotted support and broken away and exploded to show the stop for limiting movement of the assembler slide and line of matrices into the elevator;

5 Fig. 2 is a perspective view of a matrix of a type suitable for use with the present device;

Fig. 3 is a vertical section through the elevator showing a composed line of matrices positioned therein;

10 Fig. 4 is a fragmentary front elevation of the assembler slide and associated parts showing the rear wall of the elevator and a line of matrices partially removed from the assembler slide by the elevator;

15 Fig. 5 is a front elevation of a portion of the photocomposing machine showing the composing device after it has been inserted in the machine. Also shown in the lower right-hand portion of Fig. 5 are the line-length adjusting mechanism and an index assembly to facilitate setting of the composing device;

20 Fig. 6 is a top plan view of a portion of the line-length adjusting mechanism and shows the manner in which the gauging member of the composing device is positioned with respect to the line-length index to insure proper relative adjustment of the assembler slide and gauging member;

25 Fig. 7 is a vertical section taken on the line 7—7 of Fig. 6, except that in Fig. 7 the composing device has been inserted in its channel, whereas in Fig. 6 the channel is shown without the composing device therein. Fig. 7 shows the slotted support of the composing stick in operative position in the machine and the assembler slide at its left-most position, wherein it supports a line of matrices within the elevator;

30 Fig. 8 is a broken vertical section taken on the line 8—8 of Fig. 5 and showing the relationship between various parts of the composing device and its supporting channel, as well as the drum scale and line length index.

35 Referring to the drawings and more particularly to Fig. 1, the composing device there shown includes a slotted support generally designated 10 and comprising a base 12 having a longitudinal slot 14 therein, a relatively high rear wall 16 and a relatively low front wall 18. The base 12 and walls 16 and 18 form a channel within which is positioned an assembler slide 20 having a longitudinal slot 22 therein that registers with the slot 14 and an upstanding end wall 24. The slide 20 is provided with a curved right-hand end 26 to facilitate manual movement of the slide with respect to support 10.

40 Adjustably mounted on assembler slide 20

55

there is an adjustable guide 28 having an up-standing wall 30 aligned with the wall 24 of slide 20. The guide 28 is adjustably secured to slide 20 by means of a rotatable locking member 32 and a stepped shoe 34. Referring particularly to Fig. 4, the locking member 32 is provided with a laterally extending handle 36 and a downwardly projecting pin 38 that is threaded into the shoe 34. The upper step 40 of shoe 34 slides in the slot 14 of support 10 and the lower step 42 provides a flange that prevents disengagement of slide 20 and guide 28 from support 10. The upper step 40 also provides a stop to limit movement of assembler slide 20 with respect to support 10 in a manner described below.

Reverting to Fig. 1, the steps 40 and 42 are of such height that when the locking member 32 is rotated counter-clockwise, the guide 28 is securely fastened to the slide 20, and the slide 20 is freely slideable with respect to support 10. The pin 38 is preferably provided with a left-hand thread so that when the member 32 is rotated to fasten guide 28 to slide 20, the handle 36 is positioned close to the wall 16 and hence is out of the way of the composer and does not interfere with insertion of the composing device into the machine. The guide 28 may be adjusted with respect to slide 20 by rotating locking member 32 clockwise to such an extent as to permit the pin 38 to slide freely in slot 22 of the assembler slide. The guide 28 and slide 20 are initially so adjusted as to provide a space between walls 24 and 30 equal to the desired line length. When the desired spacing has been achieved, locking member 32 is rotated counterclockwise to fasten the guide and slide together and a line of matrices, like, for example, the matrix of Fig. 2, is hand composed in the space between the walls 24 and 30.

Proper relative positioning of walls 24 and 30 can be conveniently effected by utilizing the line-length adjusting mechanism shown in the drawings. Referring particularly to Figs. 5, 6 and 8, the line-length adjusting mechanism there shown is generally similar to that disclosed in Patent No. 2,552,382. It comprises generally an index member 44 that is adjustable with respect to a drum scale 46, and a hand wheel 48 for effecting relative adjustment of the index member and drum scale. Referring particularly to Figs. 6 and 8, the hand wheel 48 has a forwardly extending handle 50 and on its rear face is provided with a bevel gear 52 that meshes with a second bevel gear 54 secured to a threaded rod 56. As best shown in Fig. 8, rod 56 is threaded into index member 44 and the index member has a forked end 58 that embraces a fixed rod 60 which prevents rotation of index member 44 with rod 56, and thereby produces movement of index member 44 along scale 46 as the rod 56 is rotated. Thus rotation of hand wheel 48 moves index member 44 with respect to drum scale 46. As indicated particularly in Figs. 5 and 8, the drum scale 46 is provided around its periphery with a series of scales having point sizes marked thereon, and the drum scale can be rotated by means of a manual knob 62 secured thereto to present the desired scale for cooperation with index member 44, all as more fully described in Patent 2,552,382.

Still referring to Figs. 5, 6 and 8, the index member 44 and drum scale 46 are located in a housing 64 at the lower front left-hand portion of which is provided a notched member 66 formed to receive the wall 24 of assembler slide 20 of the device of Fig. 1. Referring particularly to Fig. 6,

in adjusting the guide 28 with respect to assembler slide 20 the wall 24 is inserted in notch 66 and the wall 30 of guide 28 is positioned opposite the index member 44. In this way, the walls 24 and 30 can be made precisely equal to the desired line length.

When a line of matrices has been composed in the composing device 10, it is inserted in the machine in a manner now to be described. Referring particularly to Figs. 6, 7 and 8, secured to the top of housing 64 is a channel member 68 which is attached to the housing in any suitable manner such as by means of the screws 70. As best shown in Fig. 8, the channel member 68 is adapted to slidably receive the slotted support 10 of the composing device which is retained in place in the channel member 68 by a plate 72 secured to the channel by the screws 74 (see Fig. 6) and overlying the channel. As illustrated in Fig. 5 of the drawing, the composing device slides into channel member 68 until its left-hand end strikes an abutment 76 forming part of an elevator 75 that is described below. The engaging edges of abutment 76 and slotted support 10 are aligned with the left end of housing 64.

As previously indicated, the composed line of matrices is transferred from the composing device to a justifying station by apparatus that includes the elevator 75, the construction of which is best shown in Fig. 3. Referring to this figure, the elevator 75 is of U-shaped cross-section and comprises a front arm 76, rear arm 78 and interconnecting block 80. Referring to Fig. 7, the composed line of matrices is inserted into elevator 75 by manually grasping the curved end 26 of assembler slide 20 and urging the left-hand end of the assembler slide between the upper ends of arms 76 and 78 until the upper step 40 of shoe 34 engages the end of slot 14. The slot 14 is of such length that when it is engaged by the step 40 the composed line will be properly positioned within the elevator.

Reverting to Fig. 3, the matrices are provided with upper ears 82 and lower ears 84 that extend laterally beyond the sides of the assembler slide 20. The arms 76 and 78 of elevator 75 are provided with the shelves 90 and 92 respectively positioned to engage the upper ears 82 of the matrices of the line. Thus as the elevator 75 is lifted, the composed line of matrices is moved thereby from the assembler slide 20. This removal of the line of matrices from the assembler slide is particularly shown in Fig. 4.

The manner of operation of the present composing device should be largely apparent from the foregoing description thereof. The index member 44 is initially set by rotation of hand wheel 48 to the point on drum scale 46 corresponding with the desired line length. Thereafter wall 24 of the assembler slide 20 is inserted in notch 66 and guide wall 30 is positioned with its left face aligned with the index member. Locking member 32 is then rotated by means of handle 36 to lock the guide 28 and assembler slide 20 securely together.

A slide of matrices, comprising, for example, matrices such as shown in Fig. 2, is then composed between walls 24 and 30, and the composing device is inserted in the machine by sliding slotted support 10 into channel 68 until the left end of the slotted support reaches abutment 76. Thereafter the curved end 26 of the assembler slide is grasped and the assembler slide moved to the left as far as it will go, that is, until step 40 reaches the left end of slot 14. In this position of slide

20, the guide wall 30 is approximately aligned with the right hand end of elevator 75 and the line of matrices is positioned within the elevator. Upon lifting of the elevator, the line of matrices is removed as a unit from the assembler slide 20, and the composing device can then be removed from the machine for composition of another line of matrices.

From the foregoing description it is apparent that the composing device of the present invention is capable of achieving the several objects outlined at the beginning of the present specification. It is of course to be understood that the foregoing description is illustrative only and that both the structure and the manner of use of the present composing device can be modified without departing from the spirit of the invention as defined in the appended claims.

I claim:

1. A hand composing device for use in composing a line of character-bearing typographical elements comprising in combination, a slotted support, an assembler slide, slidable in said slot and having a vertical wall against which said elements may be composed, an adjustable guide mounted on said assembler slide and movable with respect to said wall to define the desired line length, and locking means for locking said assembler slide and adjustable guide together, while permitting them to slide freely with respect to said slotted support.

2. A hand composing device for use in composing a line of character-bearing typographical elements comprising in combination, a channel-shaped support having a slot formed in its bottom wall, an assembler slide mounted for sliding movement in the channel of said support, said assembler slide comprising a slotted base and an upstanding end wall, a guide member adjustably mounted on said assembler wall and having an upstanding wall confronting the end wall of said assembler slide and adjustable with respect thereto to define the desired line length and means for locking said assembler slide and guide member together.

3. A hand composing device for use in composing a line of character-bearing typographical elements comprising in combination, a channeled support having a slotted base, an assembler slide comprising a base slidable in the channel of said support and having a slot registering with the slot of said support, said assembler slide having

an upstanding wall against which said line of elements can be set, a guide member mounted on said assembler slide and having an upstanding wall adjustable with respect to the wall of said assembler slide to define the length of line desired and locking means mounted on said guide member and extending through the slots of said assembler slide and support for locking said assembler slide and guide member together and permitting them to slide as a unit with respect to said support.

4. A hand composing device according to claim 3 wherein said locking means includes a shoe slidable in the slot of said support and cooperating with the ends of said support slot to limit the movement of said assembler slide and guide member with respect to said support.

5. A hand composing device for use in composing a line of character-bearing typographical elements comprising, in combination, a channel-shaped support having a slotted base, a relatively low front wall and a relatively high rear wall, an assembler slide comprising a base slidable in the channel of said support and having a slot registering with the slot of said support, said assembler slide having an upstanding wall against which said line of elements can be set, a guide member mounted on said assembler slide and having an upstanding wall adjustable with respect to the wall of said assembler slide to define the length of line desired, a rotatable locking member mounted on said guide member and having a threaded pin extending through the slots of said assembler slide and support, and a shoe threaded on said pin, said locking member and shoe cooperating to lock said assembler slide and guide member together.

6. A hand composing device according to claim 5 wherein said shoe includes an upper portion normally positioned for sliding movement in the slot of said support and a lower portion wider than said support slot to prevent disengagement of said assembler slide and support.

7. A hand composing device according to claim 3 wherein the upstanding walls of said assembler slide and guide member are of substantially the same height and terminate at points above the front wall and below the rear wall of said channel-shaped support.

GEORGE J. H. SAUSELE.
